Filed Feb. 3, 1965, Ser. No. 83,675

Term of patent 14 years

(Cl. D14—30)

FIG. 1

FIG. 2

FIG. 3

FIG. 4

FIG. 1 is a perspective view of a wheel embodying the present invention;

FIG. 2 is a fragmentary perspective view illustrating the configuration of the transparent body of the wheel;

FIG. 3 is an elevational view of one side of the wheel, the opposite side being identical in appearance;

FIG. 4 is a sectional view taken along line 4—4 of FIG. 3.

The characteristic features of our design reside in the dual faces of the transparent wheel which extend from the axial plane of the rim and terminate at the hub.

We claim:

The ornamental design for a wheel, substantially as shown and described.
